UNITED STATES PATENT OFFICE.

ADNAH McMURTRIE, OF NEW YORK, N. Y.

CONNECTOR FOR ELECTRICAL CONDUITS.

1,036,296.

Specification of Letters Patent. Patented Aug. 20, 1912.

Application filed September 17, 1907. Serial No. 393,329.

To all whom it may concern:

Be it known that I, ADNAH McMURTRIE, of New York, N. Y., have invented certain Improvements in Connectors for Electrical 5 Conduits, of which the following description, in connection with the accompanying drawings, is a specification, like letters on the drawings designating like parts.

This invention relates to electrical conduits and has for its object a "box connector" or device for connecting the ends of electrical conduit armor tubes, armored conductors, and the like in place adjacent and in communication with apertures usually 15 provided in the walls of outlet boxes or similar electrical conduit members.

My invention is of particular utility when embodied in a connector for securing the spirally wound flexible metallic armor or 20 fibrous sheath of a conductor in place at its point of union with an outlet box, although it will be understood that I contemplate the utilization of my invention in any field for which it may be adapted by the nature of 25 my improvements.

Briefly stated my device comprises an attaching portion, preferably provided with a screw threaded neck to pass through the conduit aperture in an outlet box and receive a 30 lock nut within the box, and a connecting portion preferably integral with the attaching portion to extend outward from the wall of the box to form a seat for the conduit, the latter being secured to the seat by 35 a separate flexible strap portion preferably secured to the connector portion adjacent the seat and having fastening means such as a set screw, stove bolt or the like, to enable the strap to be secured in adjusted position 40 around the armor tube, clamping the latter firmly against the seat.

The various features of my invention will be illustrated and described fully in the accompanying drawing and specification and 45 pointed out in the claims.

Figure 1 of the drawing shows in side elevation, partly in section, an electrical conduit box, with apertures to which are attached connectors in the construction of 50 which my improvements have been embodied. Figs. 2 and 3 illustrate, in front elevation, modified forms of connector with seats of polygonal section; and Fig. 4 is a vertical, longitudinal sectional view of a coupling 55 in the construction of which my invention has been embodied.

In the embodiment of my invention selected for illustration and description to enable ready and complete understanding of my improvements, the reference numeral 1 designates the attaching portion of the "box connector," 2 designates the seat, and 3 the connector strap, 4 being the fastening means, which in the instance illustrated, takes the form of a "stove bolt" passing through lugs 60 5 in the end portions 6 of the strap, which I prefer to pass around outside the bottom of the connector seat and to secure the same thereto, as by the finger 7 formed by an integral ridge divided from the periphery of 70 the walls of the seat by a tangential slot 8 in which lies the strap, the tip of the finger being bent down to engage the strap and prevent its displacement from the slot.

The reference numeral 9 designates a 75 rounded shoulder formed within the attaching portion 1, and is preferably slightly less in diameter than the inside diameter of the armor tube shown in place at 10 within the seat 2, where it has been secured by tightening the stove bolt and compressing the strap into close and binding engagement with the spiral coils of the armor, the flexible strap preferably being swaged as at 11 to correspond in form with, and to enter the spiral 85 convolutions and aid thereby to prevent displacement of the tube.

The reference numeral 12, designates a lock nut provided upon the threaded exterior of the attaching portion. 90

While the structure just described furnishes a very simple and inexpensive, but highly efficient means for accomplishing the purpose set forth, it may be modified in its details of construction as found desirable to meet the exigencies of the various situations where it may be used, and one such modification is illustrated at 13, this numeral designating a flange integral with the connector seat 14, which extends from an attaching portion 15 similar to that already described, being substantially semi-cylindrical, the flange having a hole 16, preferably threaded to receive an attaching screw 17, which passes through the ends 18 and 19, respectively, of a metallic connecting strap 20, the screw acting both to hold the strap normally in place and to bind it into engagement with an armor tube as already described with reference to the strap 3. The end 19 of the 110 strap will preferably be bent around the flange as indicated at 21, so that the screw

will pass through it twice. In both instances, the strap will be found to furnish an efficient electrical connection between the armor and the connector, and ordinarily the 5 larger the area of contact between the strap and the armor, the better will be the electrical connection, so that for this reason as well as for ease in adjustment of the parts, I prefer to form the seat portion substantially 10 semi-cylindrical, although I do not limit myself to this exact proportion of the parts, nor to a seat of circular cross section, as it is often desirable to make the seat of polygonal contour as at 22 in Fig. 2 or at 23 in 15 Fig. 3, these modifications in the cross-section of the seat being designed to afford a firm grip on the sheath at a relatively few points.

I contemplate also the use of my flexible 20 strap coupling to join two lengths of conduit, the construction being substantially identical with that already described, except that the attaching portion will receive the end of a conduit of any suitable form, and 25 as one convenient construction the attaching portion may, as shown in Fig. 4, be threaded internally, as at 24, to receive the threaded end 25 of a well known form of a conduit tube, while the seat 26, strap 27, and the fastening means 28 and rounded shoulder 29 are similar to those already described with reference to Fig. 1.

Each end of the connector may be found 30 with parts like those designated by the reference numerals 26, 27, and 28, or other variations in the combination of parts illustrated, and in their specific construction, 35 may be adopted without departing from the

spirit of my invention, nor in general do I limit myself otherwise than as set forth in 40 my claims read in connection with this specification.

What I claim and desire to secure by Letters Patent is:—

1. An attachment for articles of the class 45 described having peripheral interstices; said attachment comprising an attaching portion, a connector seat portion, a connector strap sufficiently flexible to enter intimately the peripheral interstices of the article to be connected, means to retain said strap normally upon said device, and means to tighten 50 said strap to bind the armor tube in adjusted position upon said connector seat, substantially as described.

2. A device of the class described, comprising integrally formed attaching and seat 55 portions, and a separately formed connector strap, said seat having a peripheral slot to receive said strap and a tongue to bind said strap within said slot, and said strap having adjustable fastening means to bind it in place upon an electrical conduit to secure the latter to said seat, substantially as described.

3. A device of the class described; comprising an attaching portion; a substantially semi-cylindrical connector seat of polygonal 65 contour upon its interior face; and a flexible connector; substantially as described.

Signed at New York in the county and 70 State of New York this 30th day of August 1907.

ADNAH McMURTRIE.
